UNITED STATES PATENT OFFICE.

KARL OPPERMANN, OF MAMARONECK, NEW YORK.

STEERING-POST LOCK.

1,146,345.

Specification of Letters Patent.

Patented July 13, 1915.

Application filed May 11, 1914. Serial No. 837,869.

To all whom it may concern:

Be it known that I, KARL OPPERMANN, a citizen of the United States, residing at Mamaroneck, in the county of Westchester, State of New York, have invented certain new and useful Improvements in Steering-Post Locks; and I do hereby declare the following to be a full, clear, and exact description of the invention, such as will enable others skilled in the art to which it appertains to make and use the same.

This invention relates to improvements in locks.

The principal object of the invention is to provide a simple and novel lock for the steering post of an automobile.

Another object is to provide a lock which can be quickly and easily slipped into or out of operation and which will effectively lock the post against rotation, and be itself prevented from movement out of operative position.

Other objects and advantages will be apparent from the following description, when taken in connection with the accompanying drawings.

In the drawings: Figure 1 is a side elevation of a steering post showing my invention applied thereto and in operative position. Fig. 2 is a similar view showing the same in inoperative position. Fig. 3 is a transverse section through the sleeve and associated parts in their positions illustrated in Fig. 1. Fig. 4 is a perspective view of the lock member removed from the post.

Referring particularly to the accompanying drawings, 10 represents the outer tube of the steering post. Mounted on the floor of the car and surrounding the lower end of the post is a sleeve 11, this sleeve being provided with the attaching basal flange 12, and having its exterior surface formed with the longitudinal ribs 13 and the transverse or circumferential ribs 14. The post 10 is adapted to rotate freely within the sleeve 11, and rigidly mounted on the post, a short distance above the upper end of the sleeve 11 is a second sleeve 15, the outer peripheral face of which is formed with the longitudinal ribs 16 and circumferential ribs 17. This sleeve 15 turns with the post in the act of steering.

Arranged to be engaged around the two sleeves 11 and 15 is a split sleeve formed of two sections 18 and 19 hinged together

along one of the marginal edges 20. The other long edge of the member 18 carries a staple 21, while the other longer edge of the member 19 carries a hasp 22 for the reception of said staple. The interior faces of the members 18 and 19 are formed with the longitudinal grooves 23 and transversely extending groove 24, these grooves being arranged to receive the ribs of the sleeves 11 and 15 when the members 18 and 19 are disposed in embracing engagement with said sleeves. Thus when the members 18 and 19 are engaged around the sleeves 11 and 15, and a suitable padlock engaged through the staple, the steering post will be effectively prevented from being turned. To release the device the padlock must be unlocked and removed, and the members 18 and 19 swung open far enough to release the ribs of the sleeves 11 and 15 from the grooves of the members 18 and 19. The members 18 and 19 can thus be slipped above the sleeve 15 and to hold the same in this position there is mounted on the post 10 a ring 25 which is adapted to be received in the upper transverse groove of the members 18 and 19. In this position, it will be understood that the members 18 and 19 may be just merely swung together and the hasp engaged with the staple, it not being necessary to apply the padlock. To effectively insure the members 18 and 19 remaining in the elevated inoperative position, a spring 26 is mounted between these members having a tendency to normally throw them together.

What is claimed is:

1. A lock for an automobile steering post comprising a ribbed sleeve immovably mounted on the floor of an automobile and receiving the steering post loosely therethrough, a ribbed sleeve rigidly mounted on the steering post above the first sleeve and movable with the post, a removable sleeve formed of movable sections provided with interior grooves and arranged to be engaged in embracing relation with both of said sleeves to prevent the rotation of the post, and coöperating means carried by the sleeve sections to lock the same in engagement with the ribbed sleeves.

2. A steering post lock for an automobile including a ribbed sleeve connected with the floor of the automobile and receiving a steering post rotatably therethrough, a second ribbed sleeve secured to the steering post and movable with the post to align the ribs

of the said sleeve with the ribs of the first sleeve, a sectionally interiorly grooved sleeve arranged to be engaged around the ribbed sleeves, and a rib carried by the post 5 for engagement with the grooved sectional sleeve to hold said sleeve out of operative relation with the ribbed sleeves.

In testimony whereof, I affix my signature, in the presence of two witnesses.

KARL OPPERMANN.
